UNITED STATES PATENT OFFICE

1,988,208

BOOKBINDING MACHINE AND METHOD

Laurence C. Martin, Chicago, Ill., assignor to
 Martin Machinery Corporation, New York,
 N. Y., a corporation of New York

Application April 16, 1934, Serial No. 720,902

4 Claims. (Cl. 11—1)

This invention relates to improvements in bookbinding machines and method of bookbinding and is more especially applicable to that form of binding, accomplished without stitching or 5 stapling, where a plurality of sheets have their edges glued together.

In this form of binding, a plurality of sheets are clamped together, the edges to be bound are trimmed and then roughened, and the glue is then 10 applied. In the practice of this method, however, in the past, two difficulties have been encountered. In the first place, the roughening means, usually a saw, in performing its work, leaves some dust on the edges of the sheets. This dust has interfered with the proper application of the glue. 15 In the second place, it has been found difficult or impossible to secure the proper penetration of the glue between the sheets. A thin glue is ordinarily used to hold the sheets together and to do 20 this it ought to penetrate between the sheets for a short distance from the edges. The sheets have to be clamped together rather securely, however, and this clamping has prevented the proper penetration of the glue.

25 By the practice of my invention, both of the objections mentioned above are lessened or eliminated. I provide means for effectively removing the dust left by the roughening means. In general, this includes a suction nozzle following 30 the roughening means. I also contemplate placing the suction nozzle just ahead of the glue applicator. I believe that if this is done, there may be temporarily created a reduced pressure between the sheets for a short distance from the edges. 35 With a proper speed then, the sheets may be moved to the glue applicator so that re-entry of air following the suction means will cause the glue to penetrate properly between the sheets.

Other features and advantages of my invention 40 will appear more fully as I proceed with my specification.

In that form of device embodying the features of my invention shown in the accompanying drawing—

45 Figure 1 is a view taken as indicated by the line 1 of Fig. 2; and Fig. 2 is a view in side elevation.

As shown in the drawing, A, B and C indicate 50 groups of sheets to be bound into books. The sheets of each group are held together by suitable clamp members, the details of the necessary clamping mechanism not being shown. Suitable means, well known in the art, are provided for moving or feeding the groups of sheets, at the 55 required speed, in the direction indicated by the

arrow, so that they will pass in sequence over the cutter or trimmer, roughening device, suction means, and glue applicator.

The cutter or trimmer is here shown as a circular knife indicated by 11.

The roughening device is a circular saw 12, the upwardly pointing teeth 12^a of which engage the edges of the sheets to roughen them so that the glue will adhere better.

The suction means is indicated by 13. This 10 may be a suction nozzle similar to that used on a suction or vacuum cleaner. The mouth of the nozzle may be provided with a sliding orifice plate 14 so that the effective opening of the nozzle may be adjusted to fit books or groups of sheets of 15 different thicknesses. It is to be understood that suitable means (not shown) are provided for exhausting air from the nozzle in the direction indicated by the arrows to give the requisite low pressure or suction in the nozzle. As stated in the 20 fore part of the specification, this nozzle removes the dust left on the edges of the sheets by the saw 12, and possibly may aid the penetration of the glue by temporarily reducing the air pressure 25 between the sheets adjacent their edges.

Immediately following the suction nozzle is the 30 glue applicator, here shown as a rotating drum 15 dipping into the glue container 16 holding the liquid glue 17. The upper edge of the drum applies glue to the edges of the sheets. 18 is a 35 scraper to remove excess glue from the drum.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention, as broadly as permissible, in view of the prior art.

What I claim as new, and desire to secure by Letters Patent, is:

1. A bookbinding machine, including; means 45 for clamping a plurality of sheets; means for roughening the edges to be bound; suction means for removing the dust left by such roughening means; and means for applying glue to the edges.

2. A bookbinding machine, including; means 50 for clamping a plurality of sheets; means for roughening the edges to be bound; suction means for removing the dust left by such roughening means; and means for applying glue to the edges immediately after the operation of the suction 55

means, whereby re-entry of air between the sheets aids the penetration of the glue.

3. The method of binding books, comprising; clamping the sheets; roughening the edges to be bound; removing the dust (left by the roughening means) by suction means; and immediately thereafter applying glue so that re-entry of air between the sheets will aid the penetration of the glue.

4. The method of binding books, comprising;

clamping the sheets; roughening the edges to be bound; removing the dust (left by the roughening means) by suction means; and immediately thereafter applying glue so that re-entry of air between the sheets will aid the penetration of the glue. 5
